UNITED STATES PATENT OFFICE

RODNEY N. McCLURE, OF INGLEWOOD, CALIFORNIA

DRAPERY ROD

Application filed September 14, 1926. Serial No. 135,331.

This invention relates to improvements in curtain fixtures and more particularly to fixtures for hanging curtains and drapes over windows of the swinging or hinged type.

5 In the hanging of curtains at French, casement or hinged windows it is desirable to provide for the holding of the curtains at their sides to overlap the window frame for full and complete screening of the opening 10 in a manner to not interfere with the movements of the window in its hinges.

Among the objects of my invention is to provide a fixture of simple, durable and inexpensive construction, upon which curtains 15 and drapes may be hung to completely screen the window opening and which drapes are movable with the window and include mountings for the fixtures independent of the mountings of the window.

20 Another object is to provide a curtain fixture comprising a rod having means for hingedly mounting its one end and means for fixedly mounting its other end and consisting of relatively slidably sections to provide 25 length variation at times when the fixed end is swung relatively to the hinged end and to provide means in the rod to resist the lengthwise movements of the rod sections for retaining the window at selected angles in its 30 movements upon its hinges.

My improvements consist in the novel construction, arrangement and combination of parts, as hereinafter fully, clearly and concisely described, definitely pointed out in my 35 claims and illustrated by the accompanying drawing, (1 sheet) in which:—

Fig. 1 is a sectional plan view of a hinged window and frame equipped with a curtain fixture embodying my improvements;

40 Fig. 2 is an inside face view of the fixture as mounted;

Fig. 3 is a sectional plan view as taken on the line 3—3 of Fig. 2 showing means for adding friction at the meeting ends of the 45 companion rod members;

Fig. 4 is a perspective view of the several parts of the fixtures;

Figs. 5 and 6 are perspective views of special fixtures for the mounting of a plurality 50 of curtain rods at their fixed ends.

Referring more specifically to the drawing, 10 designates a window, or door frame, 11 a window or door and 12 the hinge support for the window or door, all of which may be or are, of any approved standard construction. 55

The rod for the support of the curtains or drapes, comprises two parts A and B, having their meeting ends slidably related, as by forming them of channel section, as shown. At the free end of the rod section B there is a bend 13 for its fixing to the window sash. For this fixing I provide a fixture C which comprises a plate-like body 14 for attachment to the inside face of the sash and from which projects an arm 15 over which the channelled and bent end 13 of the rod is slipped and frictionally held, the arm, by preference, being tapered lengthwise to the end of forming a wedge like friction joint between the arm and rod. 60

At the outer end of the rod section A is a hinge element 16 carrying a stem 17 which is positioned and secured in the channel end of the rod and which provides for its fixing to the window frame. For this fixing, I provide a fixture D comprising a plate-like body 18 from which projects relatively spaced arms 19, whose free ends are provided with aligned perforations 20 through which a pintle 21 may be extended and upon which the curtain 80 rod may be swung. 70

It will be obvious, see Fig. 1, that there is provided a curtain supporting rod whose body or middle section is held spaced from the face of the sash, so that a curtain held thereby will hang outside of a window shade, such as E, and that the sides of the curtain may be drawn to and carried to the face of the sash and frame so that the curtain will form a full and complete screening of the window opening. The bent end 13 of the rod element B and arm 15 of the fixture C and the arms 19 of the fixture D which form continuations of the rod proper are for this purpose. 85

With the fixtures C and D established, the 95 rod element A hinged to the arms 19 and the bent end 13 of the rod element B freed from the fixture C, the curtain is threaded over the rod elements A and B and over the arms 19 of the fixture D. The bent end 13 of the 100

rod element B is then slipped over the arm 15 of the fixture C and the curtain drawn over the end 13 and arm 15, so that the curtain is continuous from face to face of the sash at one side and the face of the frame at 5 the other side and overlies the entire window opening.

In Figs. 5 and 6 there is shown special fixtures F and G, which provide for the hanging of a curtain and an over drape and which 10 provide a plurality of arms 15' and arms 19' to receive and hold a plurality of rods in the same manner as the single rod fixture described. The fixture F carries a channelled stem f for connection with the fixture C 15 after the manner of the bent end 13 and the fixture D carries a tapered arm d for receiving the channel stem g of the fixture G.

It will be understood that on swinging the 20 window sash, the rod elements A and B will slide relatively to each other because of the pintle 21 being positioned out of axial alignment with the pintle of the sash hinge 12; the rod being shortened as the sash swings outwardly and being lengthened as the sash 25 moves inwardly.

As best shown in Fig. 3, the meeting ends 30 of the rod elements A and B are formed with undulations a and b which co-act to produce a relative binding of the meeting ends of the rod element and thereby tend toward holding the sash against movements upon its hinges. The undulations thus serve to automatically 35 yieldably oppose longitudinal movement of the rod elements A and B in relation to each other.

I claim:—

1. A curtain fixture consisting of a fixture 40 for attachment to a window frame, a fixture for attachment to a window sash, a fixture comprising a plurality of hinging points, means for detachably and rigidly connecting the last mentioned fixture to the fixture for attachment to the window frame, a fixture 45 comprising a plurality of arms, and means for detachably and rigidly connecting the last mentioned fixture to the fixture for attachment to the window sash, said fixtures having the plurality of hinge points and the plurality of arms providing for the hanging of 50 a plurality of curtain rods.

2. A device of the class described comprising 55 a fixture for attachment to a window frame, a fixture for attachment to a hinged window sash, a rod for extension between said fixtures, means for hingedly connecting one end of said rod to one of said fixtures, and means for detachably connecting the other end of said rod to the other of said fixtures 60 in fixed relation thereto, whereby said rod is operable to vary its length by swinging the sash, said rod having resilient telescoping sections with opposed undulating surfaces adapted to yieldingly maintain the sash in 65 various predetermined open positions.

3. A device of the class described comprising 70 a fixture for attachment to a window frame, a fixture for attachment to a hinged window sash, a rod for extension between said fixtures, means for hingedly connecting one end of said rod to one of said fixtures, and means for detachably connecting the other end of said rod to the other of said fixtures 75 in fixed relation thereto, said rod consisting of telescoping sections, cooperative means on said sections for automatically forming yielding predetermined stops for the window as it swings open.

In testimony whereof I have affixed my signature.

RODNEY N. MCCLURE.
